UNITED STATES PATENT OFFICE.

GRAFTON E. LUCE, OF CHICAGO, ILLINOIS.

COLLAPSIBLE ARCHFORM FOR BRICKKILNS.

Application filed April 5, 1923. Serial No. 630,136.

To all whom it may concern:

Be it known that I, GRAFTON E. LUCE, a citizen of the United States, and a resident of Chicago, in the county of Cook and State of Illinois, have invented an Improvement in Collapsible Archforms for Brickkilns, of which the following description, in connection with the accompanying drawings, is a specification, like letters on the drawings 10 representing like parts.

My present invention is a form adapted for use in the building of the firing arches in brick kilns, and is made movable or collapsible to facilitate wetting up, removal, 15 and successive use.

In the building of brick kilns, as heretofore practiced, it has been customary to set the firing arches, particularly the top courses, closing the top of the arch by hand, 20 and without any other ruling or guidance than the eye of the worker. This work being on the inner faces of the arch, especially in the operation of building the second or closing half of the arch, it has been considered impossible to use any guide, rule, 25 form or other aid to the eye of the worker. As these arches extend entirely through the brick kiln, usually from 40 to 50 feet in length, the alining or truing up of the brick, 30 especially that at the top courses closing in the arch, has been extremely difficult. Furthermore, in the employment of certain types of mechanical setters, it is not only important but necessary to have some means to unload the setters, affording a substantially solid resistance for backing off the 35 setter during the unloading.

In developing a collapsible form for the purpose above explained, I have devised a 40 novel, simple, and efficient apparatus capable of repeated and continuous use and suitable to the position at any point on the kiln ground for the setting of arch, and especially for the determining, alining and establishing of the arch face throughout the 45 entire width of a kiln and of sufficient strength and rigidity to afford the resistance necessary for "backing off" a mechanical setter of the type of my said prior patent. 50 My present collapsible form is portable, adjustable, and capable of being left in the kiln until the entire arch is completed, and then collapsed and withdrawn. For this 55 purpose I mount the principal framework

suitable sets of wheels, the entire frame being of any desired length, preferably one-half the width of the kiln, so that a form may be fitted in from either side of the arch to be built. When so positioned, the engaging devices are set to automatically space, aline and determine the kiln face of the brick arch to be built. For this purpose also I provide novel and efficient means to adjust and to hold the brick engaging devices at any width and height—within a considerable range—for the setting of the arch. It will be appreciated that brick to be set in a kiln are of constantly and continually varying size, because of varying conditions in manufacture, drying and shrinkage. The condition of the weather has a large and important bearing in the process of brick manufacture. Also, brick made at different locations are of different desired dimensions. 60 My apparatus is designed to take care of all these inequalities and difficulties, and to be instantly and automatically ready for such varying dimensions in the brick, both in height and width of arch, as well as in the thickness of the several courses. This is of 65 the greatest importance in the upper courses or "jets" when closing in the arch. Important objects, therefore, are to provide a collapsible form suitable to remain within 70 the arch until it is entirely completed, which will true up and aline both sides of the arch, which will particularly predetermine and support the jets or overhanging bricks when closing in the arch and yet which will be 75 instantly collapsible and provide clearance 80 simultaneously both downwardly and inwardly when it is desired to withdraw the form. Brick when built into a kiln is, of course, soft or green brick, and the lower 85 benches from which the arches are made, are constantly subject to compression and settling. Furthermore, the overhanging brick forming the jets, being soft, will tend 90 to pitch forward and drop downwardly, being thus disaligned in respective courses. My collapsible form, by providing a suitable support at the right height and in position 95 to aline the brick, both vertically and horizontally, support and maintain the jets at 100 the proper level until the superimposed courses of brick have been set and the entire lower benches and arches have become settled and in their permanent position. Thereupon my improved form can be collapsed, 105 110

and withdrawn and used in setting subsequent arches.

Being capable of continuous use only a few collapsible forms are necessary for the building of an entire kiln of 50 arches. By using my form it is practical to set softer brick than would otherwise be capable of standing up in the lower benches and arches of the kiln, which is an important practical 10 advantage in kiln building.

In setting a kiln by means of my apparatus, the entire arch through its length, width, and height, as well as the entire kiln, are thus automatically alined and spaced 15 and of much greater uniformity, than otherwise, thus aiding the burning operation, rendering the same more uniform and varying disarrangements of successive arches is entirely eliminated.

20 My present collapsible form contains means which will withdraw a brick engaging device after the arch is completed or the kiln set and settled, or when the lower benches and arches have received the normal weight of the upper portions of the kiln, by a simultaneous contracting movement both inwardly and downwardly. It will be realized that it is of great importance to get such a form out of the arches 25 without injury to the soft green brick and particularly without damage to the overhanging corners and brick projecting into the top of the arch. For this purpose I provide mechanism which will automatically collapse the entire form, viz, draw inwardly 30 the brick engaging devices or members on the legs or vertical sides of the arch and which will draw downwardly and inwardly the brick engaging members on which the top courses of the arch rested and touched. The topmost members being substantially 35 in a corner, are moved immediately away from both the face of one brick and the bottom of the next superimposed brick, thus collapsing the form in a diagonal or angular direction. This movement may be effected in any desired manner, but as herein shown I prefer to employ a single operating wheel which will extend lengthwise of the form, will engage toggle members or the like at a plurality of points carrying the side bats, and so connect the operating wheel that the entire upper arch of the form will be lowered simultaneously with the inward 40 movement of the side bars, thus effecting the collapsing action both inwardly and downwardly and giving immediate clearance to all face of the green brick previously in contact with the form. Furthermore this collapsing action is effected and the entire form freed from contact with the arch on both sides as well as the top, while the apparatus still stands in its normal position within the arch and before it 45 is started for movement out of the arch.

Once collapsed it is readily withdrawn on its wheels and re-positioned at another point in the kiln, or in a subsequent kiln, for use. The brick engaging devices are expanded to the position desired and the arch set. The collapsing and expanding mechanism, as will be explained, enables the form to be automatically held in any position to which it is expanded or withdrawn, without further locking devices. The brick engaging 70 members are thus automatically locked wherever set, by one single adjustment, which adjustment also effects the lateral expansion and the elevation of the form. 75

I believe that my invention of a suitable and practicable form for use in setting the arches of a kiln, especially for setting such arches by means of mechanical brick setters, is a distinct novelty in this art, and I intend herein to claim such forms broadly 80 and particularly a collapsible form, it having heretofore been the universal custom to set kilns without employing any form whatever in the arches. My invention provides a positive, definite, mechanical means 85 to aline, support, and as a guide for the building of the kiln, particularly in setting the lower benches and this is an important advantage in the process of brick manufacture. 90

95 Referring to the drawings, illustrating a preferred embodiment of the invention,

Fig. 1 is a side view of my collapsible form with parts broken away to better illustrate same;

100 Fig. 2 is a plan view;

Fig. 3 is an enlarged view of the opening of an arch, showing the form in expanded position, in contact with the brick;

Fig. 4 is a view corresponding to Fig. 3 105 illustrating the form in collapsed position and ready to be withdrawn from the arch;

Fig. 5 is a fragmentary cross-sectional view on the line 5—5 of Fig. 4;

Fig. 6 is a fragmentary plan view on the 110 line 6—6 of Fig. 3;

Fig. 7 is a view corresponding to Fig. 6, illustrating the form collapsed;

Fig. 8 is a fragmentary plan view on the 115 line 8—8 of Fig. 3, and

Fig. 9 is a corresponding view to Fig. 8 illustrating the form collapsed.

Referring to the drawings, my collapsible arch form, as therein shown and illustrated, may be of any suitable width for the width 120 of arch or kiln in which it is to be used, preferably such forms being moved into the position on the kiln floor, from each end of the arch to be built, while the form is in collapsed or contracted condition. The length, therefore, is variable, but will ordinarily be approximately twenty-five feet. An arch frame is mounted on pairs of wheels, 1 and 2, adjacent each end of the frame, an axle 3 extending therethrough. 125

These pairs of wheels, however, are not mounted directly upon the axle, but are each formed with a large centrally eccentric hub 5 bearing upon a frame 6 having corresponding eccentric hubs 7 and 8 for the wheels 1 and 2 respectively, this bearing member 6 being bored to snugly fit the axle 3, as clearly shown in Fig. 3. A covering plate 9 is provided to hold the wheels and 10 bearings in assembled position, a cotter pin 10 being fitted through the axle to retain the same in position. The member 6 has secured thereto, centrally thereof, a gear wheel 12 and on each side of said gear are 15 formed bearing surfaces 13, 13, the gear 12 being secured between shoulders 14, 14. These bearing surfaces 13, 13, constitute the supporting means for the entire framework at each end of the arch or wherever 20 the pair of wheels are positioned to carry the framework, and the entire framework, to be described, rests upon these surfaces 13, 13, at each side of the gear wheel 12, which surfaces are concentric with the axis 25 of the axle 3. On these concentric bearings the lower framework 20 having two round bearings 21, 21, are provided to rest thereon, the frame being held in place by contact with the shoulders 14, 14. This arrangement 30 is such that a partial rotation of the member 6 through the eccentric bearing of the hubs 8 and 9 in the wheels 1 and 2 respectively, will effect a bodily raising or lowering of the entire framework supported and carried 35 by the base 20. Secured to the frame 20 is a plate 22 having a pair of uprights 24 and 25, and united at the top as shown at 26. Extending longitudinally from the frame 20 is a brace or plate 30 to the next adjacent 40 pair of wheels and base member 20, a top plate 31 similarly extending longitudinally of the form. Thus a light, strong framework is provided mounted on pairs of wheels and adapted to be easily moved about the 45 kiln floor and into an out from an arch, said frame carrying the collapsible members to be now described. I prefer to mount these collapsible or contracting members to slide inwardly on this frame to secure the bodily 50 movement toward and from the sides of the brick in each face of the arch, and to effect the raising and lowering of the entire frame through the eccentric bearings of the supporting members 6 on the wheels. In order 55 to secure these two movements simultaneously by a single actuation, I provide a shaft 33, to which a wheel 34 is secured through its hub 35, and a pin 36, which shaft runs longitudinally and centrally of the apparatus. This shaft may have bearings at 60 a plurality of points and wherever an upright framework such as 24 and 25 are built, cross members 37 and 38 bolted to the uprights and affording a bearing for the shaft 33. Secured to this shaft is a gear wheel

40 adapted to mesh with a corresponding gear 41 keyed to a vertical shaft 44, extending downwardly to the gear 12 on the member 6, where the shaft 44 carries a worm 45, arranged to mesh with said gear 12. To 70 afford bearings for this construction and to protect the gears from dirt, dust, etc., I prefer to form the base member 20 with an extension 46, with a cap 47 for the lower part, belted together at 48 through lugs 49, 75 formed on either side. This gives added strength to the base 20 and enables this enclosing feature to be secured in a single casting. Consequently, rotating of the wheel 34 rotates the shaft 33 which will 80 move the side bars inwardly or outwardly—to be explained—and simultaneously raises or lowers the entire framework through the rotation of the eccentric hubs.

Secured to the uprights 24 and 25, are 85 pairs of brackets 50, 51, 52, 53, 54, and 55, each formed with an upstanding dovetailed groove to constitute fixed bearings for the correspondingly undercut grooved slides 60, 61, 62, 63, 64, and 65. The brackets 50 to 90 55 extend transversely so that the slides 60 to 65 move thereon transversely of the apparatus. To these sliding members 60 to 65 are secured slats 70, 71, 72, 73, 74, 75, 95 and 76, at each side, the slats 70 and 71 being mounted on and carried from the same slide 60 through a depending rod 69 at each side. In order to operate these slides backwardly and forwardly upon the bracket members I utilize pivoted links (see Figs. 3 and 5). These links are substantially alike and in each instance comprise a member 80 pivoted to a bolt 81 which is carried by the sliding portions 61, 62, 63, or 64. The links extend inwardly, 100 where they are pivoted at 84, 84, 84, 84, to a movable frame 85, said frame having a threaded hub 86 through which the threaded portion 87 of the shaft 33 passes at two or more points throughout the length of the apparatus. This frame 85 is formed with 105 flanges 89, and may slide on the lower central members 30, and between side ribs 189 on the topmost members 31 (see Fig. 5). A limited sliding movement is all that is 110 required of this frame 85 in order to carry the pairs of links either forwardly or backwardly past their extreme perpendicular position to collapse the same and slide the slats 70 to 76 inclusive on each 115 side inwardly, thus collapsing the frame. It will be seen that this arrangement of the sliding frame 85, to which are pivoted the 120 links actuating the right angled slides 61 to 65, enables these right angled slides and the brick contacting slats carried thereby to be moved inwardly and outwardly, freely and simultaneously, without binding and with a minimum of effort, as well as maximum of speed. Furthermore, when desiring 130

to expand the frame, the advantages of a toggle motion are secured, as the shaft 33 is manipulated, to move the links to their position perpendicular with the frame 85, as said frame is slid longitudinally of the apparatus. It will be understood that the links are shorter for the topmost members, where the arch is narrower, but the mode of operation and actuation is the same. As shown in Figs. 6 and 7, for example, the links at this point near the top of the arch, 90, 90, are pivoted to the same stud 91 carried on the sliding frame 85, and in order to secure a substantially uniform actuation on these shorter links as that obtained on the longer links 80 (see Figs. 8 and 9), when moving from collapsed position to expanded and from expanded to collapsed, I provide a sufficient leeway or "dwell" by forming the inner ends of the links 90 as they encircle the bolt 91 with a slightly elongated slot, as illustrated at 92, Figs. 6 and 7. The effect of this arrangement will be readily understood and enables the completely expandible, or completely contracted position of the topmost frames 75 and 76, within the narrow confines of the closed in portion of the arch, to attain the limit of their respective inner and outer movements at substantially the same time as the lower and longer links 80, a similar proportional amount of leeway being provided for the slat carrying members 64, intermediate the top and lower links.

In the building of an arch, for a brick kiln—or for other purposes—my improved apparatus would ordinarily be left in collapsed position, in which state it would have been removed from a previously built arch and positioned next the last bench or stack of brick, diagrammatically indicated at 100, and the links expanded. Thereupon the next bench 101, usually seven brick high, would be set, by a mechanical setter, or built by hand. Preferably my apparatus is intended for use with mechanical setters, as above explained, and in certain types of setters it is necessary to have the collapsible frame of sufficient rigidity to constitute a proper resistance of "backing off" wall to enable the setter to discharge its load of brick, also as above explained. Thereupon the upper courses of brick would be "pulled" (see Fig. 3), the first course above the arch, 102, extending over and resting upon the lower slot member 73, while contacting with the upper slot member 74. This, my improved arch form has guiding and supporting means, on which to close in the arch, build the same evenly, from each side, constituting an alining, supporting and guiding apparatus for the entire arch building operation throughout the width of the kiln and length of the arch. Furthermore, such members support the inner edges of the

closing in courses of brick until the upper tiers or stacks of brick are piled and the entire arch and kiln is settled and in permanent formation. The succeeding courses, 103, is similarly set, only resting on the lower slat member 74 and abutting against the next upper member 75, while the superimposed course 104 rests upon the slat member 75 and abuts against the topmost slat 76. To provide an additional guide above the slat member 76, I prefer to make the upper slides 55, 55, with a projecting flange 106, to still further guide the top courses 107, 107, of the arch, in position and alinement, as shown.

In the operation of the apparatus, after the arch has been built, and the kiln properly settled, the operator then rotates the wheel 34 to move the sliding frames 85—of which there are two or more throughout the length of the apparatus, thus breaking the toggles effected by the link members, moving the respective slides inwardly upon their bracket guides and withdrawing the slats equally, simultaneously and instantly from the faces of the arch. As the rotation of the wheel 34 similarly actuates the entire frame to lower it, through the shifting of the eccentric bearings in the supporting wheels, the upper sets of slats 73, 74, 75 and 76 are withdrawn from the corners of the closed in part of the arch, diagonally, thus freeing the entire brick contacting devices instantly, simultaneously, and without danger of marring the corners, edges, or other portions of the green brick. The apparatus in collapsed position is illustrated in Fig. 4, and is then easily rolled out of the arch on its pairs of wheels, being ready to be positioned at any place in the kiln shed for the building of another arch, as above explained.

Furthermore, the apparatus can be adjusted for any width and height of arch desired, and the brick contacting members 70 to 76 will be held in positions intermediate the full expansion of the toggle links and contraction thereof, by the friction of the threaded shaft 33, and the hubs 86, thus still further rendering the apparatus useful and universally adjustable.

My invention is further described and defined in the form of claims as follows:

1. Apparatus of the kind described, consisting in a form for setting arches in a brick kiln, having brick engaging and alining means for both sides and top of the arch, in combination with means to withdraw the brick engaging members before the form is removed from the arch, said withdrawing means simultaneously drawing inwardly and downwardly the brick engaging members.

2. Apparatus of the kind described, comprising an arch form for use in setting

- arches in brick kilns, having brick engaging and alining members and means to adjust said members toward and from the walls of the brick arch.
- 5 3. Apparatus of the kind described, comprising an arch form for use in setting arches in brick kilns, having brick engaging and alining members and means to adjust said members toward and from the 70
10 walls and overhanging top courses of the brick arch.
4. Apparatus of the kind described, comprising a form for use in setting the arches in a brick kiln, having a plurality of spaced 75
15 brick engaging members extending longitudinally, in combination with means to adjust said brick engaging members inwardly or outwardly and to hold the same where thus adjusted.
- 20 5. Apparatus of the kind described, comprising a form for use in setting the arches in a brick kiln, having a plurality of spaced brick engaging members extending longitudinally, in combination with means to expand 80
25 said brick engaging members outwardly and upwardly.
6. Apparatus of the kind described, comprising a form for use in setting the arches in a brick kiln, having a plurality of spaced 85
30 brick engaging members extending longitudinally, in combination with means to expand said brick engaging members outwardly and upwardly, and to collapse them inwardly and downwardly simultaneously.
- 35 7. Apparatus of the kind described, comprising a portable apparatus for use in setting arches in a brick kiln, consisting in a framework mounted upon a plurality of wheels, means on said framework to carry, 90
40 at a plurality of points, brick engaging members, slideable supports carrying said brick engaging members and adapted for sliding movement transversely of the apparatus, in combination with a shaft and connecting 95
45 links, to slide said supports inwardly and outwardly.
8. Apparatus of the kind described, comprising a portable apparatus for use in setting arches in a brick kiln, comprising a framework mounted upon a plurality of wheels, means on said framework to carry, at a plurality of points, brick engaging members, slideable supports carrying said brick engaging members and adapted for 100
50 sliding movement transversely of the apparatus, in combination with a shaft and connecting links, to slide said supports inwardly and outwardly, and to raise and lower the entire framework relatively with 105
55 the supporting wheel.
- 55 9. Apparatus of the kind described, comprising a portable form adapted for setting the courses of brick in the arch of a brick kiln at different levels and spacing, having 110
60 a plurality of brick engaging slat-like mem- bers on each side, certain of said members being differently spaced from the others, and means to move all of said members outwardly in expanded condition or inwardly in collapsed condition at the same operation. 70
65
10. Apparatus of the kind described, comprising a portable form adapted for setting the courses of brick in the arch of a brick kiln at different levels and spacing, having a plurality of brick engaging slat-like members on each side, certain of said members being differently spaced from the others, and means to move all of said members outwardly in expanded condition or inwardly in collapsed condition at the same operation, and completing the limit of the outward or inward movement at the same time. 75
80
11. Apparatus of the kind described, comprising a portable framework, a plurality of pairs of wheels supporting said framework, an eccentric bearing member between said framework and wheels, whereby rotative movement of the member will effect a raising and lowering of the framework relatively with the ground and brick engaging devices carried by said frame, whereby movement of the eccentric member to effect a lowering of the frame withdraws the brick engaging members from contact with the brick. 85
85
12. Apparatus of the kind described, comprising a portable framework, brick engaging and aligning members arranged at each side of said framework predetermined brick engaging members being adapted to constitute a support for the brick in the courses closing over the arch. 100
90
13. Apparatus of the kind described, comprising a portable framework, brick engaging and alining members arranged at each side of said framework, sliding supports for said members, links to move the members on said supports, an eccentric mounting between the frame and its wheels, and means to operate the links, to slide said supports and actuate the eccentric mounting to raise or lower the frame simultaneously. 105
105
14. Apparatus of the kind described, comprising a collapsible and adjustable form for setting arches in a brick kiln, means to expand and contract the brick engaging portions of the form, and means to hold the said form in positions intermediate the extreme expanded and collapsed positions. 115
115
15. Apparatus of the kind described, comprising a collapsible and adjustable form for setting arches in a brick kiln, means to expand and contract the brick engaging portions of the form, and automatic means to hold the said form in positions intermediate the extreme expanded and collapsed positions. 120
120
16. Apparatus of the kind described, comprising a collapsible and adjustable form for setting arches in a brick kiln, means to 130
125
- 65

expand and contract the brick engaging portions of the form, and automatic means to hold the said form in positions intermediate the extreme expanded and collapsed positions, said automatic means comprising a worm and gear connection from the adjusting devices to the expanding and collapsing

members adapted to withstand compression on the brick engaging members intermediate the range of adjustability.

In testimony whereof, I have signed my name to this specification.

GRAFTON E. LUCE.
